CHANNEL OPENING MACHINE

Filed Nov. 17, 1928

INVENTOR

George H. Hatch
By his Attorney,
Kelson Howard

UNITED STATES PATENT OFFICE

GEORGE H. HATCH, OF LYNN, MASSACHUSETTS, ASSIGNOR TO UNITED SHOE MACHINERY CORPORATION, OF PATERSON, NEW JERSEY, A CORPORATION OF MASSACHUSETTS

CHANNEL-OPENING MACHINE

Application filed November 17, 1928. Serial No. 320,165.

This invention relates to channel opening machines, and particularly to those for turning the channel lips of soles preparatory to the sole attaching operation.

5 It is common in the manufacture of McKay shoes to open the channel by presenting the sole progressively to the action of a rotary channel opening tool which lifts and turns the channel lip, the sole being guided accurately 10 in the proper path by suitable channel and edge gauges. In one aspect the present invention consists in improvements in mechanism for directing and controlling the movement of the sole to the operating tool. Heretofore, the margin of the sole beneath the lip 15 has moved in engagement with the stationary surface of the channel gauge. In accordance with one feature of the present invention, the feeding movement of the sole is facilitated 20 and retarding effect substantially eliminated by providing a freely moving gauge surface 25 between the stationary channel gauge and the surface of the sole. As herein shown, the desired result is secured by providing the edge gauge roll with a flange which will travel freely with the sole and contact with it instead of the channel gauge surface.

In accordance with a further feature of the invention, the flange is arranged to form a 30 vertex with the body of the edge gauge roll for the reception of the corner edge of the sole beneath the channel lip. In this way the sole edge is confined by a continuous unbroken angular surface so that it is impossible 35 for shreds upon the edge of the sole to work under the channel gauge, as may otherwise happen to the detriment of the sole and the obstruction of the machine.

In another aspect the invention consists in 40 improvements in the sole guiding instrumentalities of such a machine as that disclosed in U. S. Letters Patent No. 1,407,037, granted February 21, 1922, on an application of J. E. Jackson. The machine therein disclosed is equipped with a driven feed wheel 45 arranged to underlie the margin of the sole and advance it to the channel opening tool. In this connection, another feature of the invention consists in a driven feed wheel 50 combined with an edge roll having a flange

between which and the body of the feed wheel the margin of the sole is engaged and fed. It will be seen that by this arrangement the opposite surfaces of the margin of the sole, as well as its edge surface, travel in 55 contact with gauge surfaces which move with the sole in its direction of travel. Drag upon the sole, therefore, is reduced to a minimum and its presentation to and passage through the machine is facilitated in a marked degree. 60

These and other features of the invention will be best understood and appreciated from the following description of a preferred embodiment thereof, selected for purposes of illustration and shown in the accompanying 65 drawing, in which the single figure is a view in side elevation, partly in section, showing so much of a channel opening machine as is necessary to understand the present invention. 70

The general organization and arrangement of parts of the machine herein shown is that of a commercial type of channel opening machine shown, for example, in U. S. Letters Patent No. 1,030,630, granted June 25, 1912 75 on an application of Henry W. Winter, to which reference may be had for a detailed description of the driving mechanism and other parts not shown.

The machine frame 8 provides bearings for a driven vertical shaft 12, having secured to its lower end the channel opening tool which comprises a wiper 10 rotating in the direction of the arrow. The wiper 10 has projecting portions shaped to engage the channel lip, 80 lift it and turn it back over the body of the sole. Cooperating with the wiper and acting subsequently to press the turned-up lip into engagement with the surface of the sole is a stationary presser foot 14, adjustably mounted in the machine frame. A channel gauge 16 is provided to enter the channel and limit the extent to which the sole may be inserted beneath the rotary wiper 10. The channel gauge comprises a thin blade having a shank 85 adjustably clamped in the machine frame by a clamping bolt 17.

The lower part of the machine frame is provided with vertical guideways 28, in which is mounted a sliding block 24, normally 100

5 maintained in elevated position by a compression spring 30. The sliding block is provided with a forward extension 32 to which is attached a treadle rod 34. Through tension exerted on this rod, the sliding block may be moved downwardly against the action of the spring 30 so as to lower the feed wheel from the wiper to facilitate the presentation of the work preparatory to the channel opening operation.

10 The sliding block 24 is provided with journals for a driven feed shaft 22 disposed at a slight inclination upwardly and forwardly in the machine and carrying at its forward end a feed wheel 42. The feed wheel has a peripheral cylindrical face, adapted to underlie and support the margin of the sole being operated upon, and a toothed disk 40 of somewhat greater diameter which imbeds itself to some extent in the sole and advances it positively to the action of the wiper.

15 The parts of the machine heretofore described are similar in construction to the corresponding parts of commercial channel opening machines such, for example, as those disclosed in the patents above identified and their operation is well understood in the art.

20 Adjacent to the periphery of the feed wheel 42 is mounted an edge gauge roll 58. This is arranged to turn freely on a vertical spindle 60, projecting upwardly from a carrier bar 62, adjustably retained in position in the machine frame by a clamping screw 64. The peripheral surface of the gauge roll 58 is inclined or tapered upwardly so that its acting face is disposed substantially at right angles to the peripheral cylindrical face of the feed wheel 42. At its upper end, the gauge roll 58 is provided with a laterally projecting flange 59 tapering so that its lower or acting face is substantially at right angles to the inclined peripheral face of the gauge roll. The upper face of the flange 59 is flat and is disposed in close proximity to the underneath surface of the stationary gauge 16. The flange 59 is thin and extends nearly to the outer effective end of the channel gauge. The combined thickness of the flange and the channel gauge is such that they may be inserted together beneath the channel lip, in which position the under surface of the flange 59 engages the upper marginal surface of the sole between itself and the peripheral surface of the feed wheel 42. It will be understood that the spring 30 acts to maintain the margin of the sole yieldingly engaged between these two members and that the acting surface of the flange 59 is oppositely disposed with respect to the periphery of the feed wheel and substantially parallel thereto or slightly divergent.

25 The flange 59 is preferably formed integrally with the edge gauge roll 58 but in any case its surface forms a vertex with the inclined peripheral face of the edge gauge roll

of continuous unbroken contour, adapted to engage the upper marginal corner edge of the sole and confine it in its passage through the machine. On this account, shreds or threads of material which may have been formed at the edge of the sole in the previous channeling operation are positively confined and prevented from being caught in the machine or torn from the sole. The inclined peripheral surface of the edge gauge roll, being located closely adjacent to the peripheral surface of the feed wheel 42, forms a lower vertex at this point for the reception of the lower corner edge of the sole margin and thus the portion of the sole beneath the lip which is being fed through the machine is engaged upon all three sides by surfaces which are moving in its direction of travel.

30 In the operation of the machine, the wiper 10 and the feed wheel 42 are continuously rotated. The feed wheel is displaced by the operator in depressing the treadle rod 34 to permit the insertion of a sole. The sole to be operated upon is placed in the machine so that the channel gauge 16 lies in the channel beneath the channel lip. The drawing shows a sole thus positioned, in cross section. As the sole is advanced against the rotary wiper 10 and the presser foot 14, the wiper exerts a rubbing action on the edge of the channel lip, raising it and bending it over and down upon the sole in cooperation with the presser foot. The spring 30 acts to maintain the sole under substantially uniform pressure between the periphery of the feed wheel 42 and the oppositely disposed flange 59 of the edge gauge roll. The edge gauge roll, meanwhile, turns freely in contact with the sole so that the latter is carried through the machine smoothly, under positive control and without the frictional resistance of any stationary part of the machine dragging upon the margin of the sole.

35 Having thus described my invention, what I claim as new and desire to secure by Letters Patent is:

1. A machine for turning sole channel lips, having in combination, a rotary wiper, and means for guiding a sole thereto including a feed wheel underlying the margin of the sole, an edge gauge roll contacting with the edge of the sole and having a projecting flange overlying the margin of the sole, and a channel gauge located above said flange.

2. A machine for turning sole channel lips, having in combination, a rotary wiper, and means for guiding a sole thereto including a feed wheel supporting the sole, and a flanged edge gauge roll arranged with its flange engaging the sole at a point opposite to the feed wheel, and with its body portion engaging the edge face of the sole to gauge the location of the sole in the machine.

3. A machine for turning sole channel lips, having in combination, a rotary wiper, and

means for guiding a sole thereto including a feed wheel, a flanged edge gauge roll arranged to engage the margin of a sole yieldingly between the periphery of the feed wheel and the flange of the gauge roll and means for limiting the extent to which a sole may be inserted beneath the wiper.

4. A machine for turning sole channel lips, having in combination, a rotary wiper, and means for guiding a sole thereto including a feed wheel and a cooperating edge gauge roll arranged to turn in contact with the edge of the sole and having an integral flange of a width less than the depth of the channel in the sole forming with the body of the roll a vertex for the reception of one corner edge of the sole.

5. A machine for turning sole channel lips, having in combination, a channel opening tool, a feed wheel, an edge gauge roll located adjacent to the periphery thereof and arranged to turn in contact with the edge of the sole, the periphery of the feed wheel and the periphery of the edge roll forming a vertex for the reception of the lower corner edge of the sole, and the edge roll having a projecting flange forming a vertex with the periphery of the edge roll for the reception of the upper corner edge of the sole.

6. A machine for turning sole channel lips, having in combination, a channel opening tool, a feed wheel, an edge gauge roll located adjacent to the feed wheel and having a thin flange spaced from the periphery thereof, and a thin stationary channel gauge disposed in close proximity to the gauge roll flange and arranged to extend with the flange beneath the channel lip.

7. A machine for turning sole channel lips, having in combination, a channel opening tool, a channel gauge disposed adjacent thereto, and an edge gauge roll having a thin flange underlying the channel gauge and forming a vertex with the body of the roll for the reception of the corner edge of the sole beneath the lip.

8. A machine for turning sole channel lips, having in combination, a channel opening tool, a channel gauge disposed adjacent thereto, and an edge gauge roll having a peripheral surface inclined with respect to the plane of the channel gauge and a flange with a sole engaging face disposed at substantially right angles to its inclined surface.

9. A machine for turning sole channel lips, having in combination, a channel opening tool, a channel gauge disposed adjacent thereto, and an edge gauge roll having a thin flange underlying the channel gauge and forming a surface freely movable with the sole between it and the channel gauge.

10. A machine for turning sole channel lips, having in combination, a rotary channel opening tool, a flat stationary channel gauge, a feed wheel having its sole engaging face

disposed at an inclination to the plane of said channel gauge, and an edge gauge roll having a projecting flange with a sole engaging surface opposed to the inclined face of the feed wheel.

In testimony whereof I have signed my name to this specification.

GEORGE H. HATCH.
